O. O. EATON.
METHOD OF LOADING CARS.
FILED JUNE 19, 1922.

UNITED STATES PATENT OFFICE.

ORRIN O. EATON, OF WATSONVILLE, CALIFORNIA.

METHOD OF LOADING CARS.

Application filed June 19, 1922. Serial No. 569,281.

To all whom it may concern:

Be it known that I, ORRIN O. EATON, a citizen of the United States, and resident of Watsonville, in the county of Santa Cruz 5 and State of California, have invented certain new and useful Improvements in Methods of Loading Cars, of which the following is a specification.

It is the object of my invention to provide a method of loading cars with perishable fruits in trays whereby the said fruits may be transported without injury and with abundant ventilation.

In the drawings:—

Figure 1 is a top plan view of a section of a car equipped with my improved method of loading cars, parts being broken away.

Figure 2 is a cross sectional end view of 20 the same, parts being broken away.

Figure 3 is a top plan view showing the method of securing the rows of trays at the center of the car, parts being broken away.

Figure 4 is an enlarged detail sectional 25 view through one end of a tray.

In shipping fresh garden produce, such as strawberries in box cars, it is desirable that they be shipped in the trays in which they are marketed without being placed in the 30 shipping crates ordinarily used. Berry trays 1 for shipping are oblong in form and contain as a rule twelve baskets of berries as 2. In placing the trays in the car I arrange them in stacks of some ten 35 trays as at 3 and then arrange the stacks with their longer sides substantially parallel with the sides of the car body 4 as at 5. Since ventilation is not required through the ends of the trays the ends of adjacent 40 stacks are placed in contact, one end of each row of stacks engaging one end of the car as at 6 and the other end being held by suitable framework built up in the center of the car as at 7, each stack being placed 45 solidly against the stack already placed so that each row of stacks is somewhat under compression longitudinally.

The sides and bottoms of each tray are 50 ventilated as at 8 as a free passage of air to the ventilated tray is necessary. Therefore the several rows are spaced apart as at 9 and from the sides of the car as at 10. To hold the several rows in their proper positions in the car, a number of cleats as 55 11 are arranged transversely of the rows

and nailed to the ends of the trays over which they pass and butted up against one or both sides of the car as shown in Figure 2 thus forming braces for supporting the stacks against lateral displacement. 60

In securing the trays in a car as above described, however, it is practically impossible to prevent movement of the trays with respect to each other unless a locking means is provided between the several trays in a 65 stack. I secure this locking of the stacked trays by providing a tray constructed in such a manner that it automatically locks against movement with respect to the tray above or below. In the embodiment herein 70 disclosed I use a tray in which the upper edge of each end is rabbeted as at 13 and the lower edge of each end carries a cleat 14 adapted to engage the rabbet 13 in the next lower tray. It is obvious that when 75 one tray is so constructed and arranged with relation to the next lower or upper tray that no longitudinal movement is possible therebetween, and then a lateral movement of one end of say, the top tray will apply a 80 twisting strain to the whole stack of trays, the twisting strain binding the several trays together so that they can only swing or move as a unit.

This action is highly important in the 85 loading method set forth because of the inaccuracies necessarily present when cross cleats 11 are used. In placing these cleats 11 in position the natural irregularities of the trays, careless placing and nailing, etc., will 90 here and there leave slight spaces between the ends of certain cleats and the sides of the car. When, now, the car swings over one way a short cleat permits a lateral movement of the ends of the trays to which it is 95 secured. This twisting of the tray, however, securely locks it to the tray below and so on down through the stack thereby keeping all of the trays in each stack effected in their proper vertical alignment. 100

In the construction and method set forth no longitudinal cleats are required and the entire load may be held in position by one set of transverse cleats on the top of the load of trays and the braces 7 in the center of the 105 car. The car may be loaded quickly because the stacks may be all trucked into position before the cleats and braces are applied whereas under previous methods the trays have to be built into a solid mass by an in- 110

tricate system of both transverse and longitudinal cleats.

The task of unloading a car in which the trays are bound by transverse and longitudinal cleats interspaced throughout the mass is a large one, while by my method it is comparatively simple since when the transverse cleats and the braces 7 are removed the several stacks may be lifted bodily and trucked 10 from the car.

It is to be understood, of course, that while I have herein shown and described one embodiment of my invention, changes may be made within the scope of the appended 15 claims. For instance, any construction of trays may be used that will prevent longitudinal movement of one with relation to the other, and any suitable form and arrangement of bracing cleats may be used to prevent lateral movement of the several stacks, under some conditions a single set of transverse cleats only being required on the tops 20 of the uppermost trays.

I claim:—

25 1. The method of loading a car which consists in arranging a stack of trays supported against longitudinal movement with relation to each other, arranging the stacks longitudinally in spaced rows in the car, bracing 30 the rows against longitudinal displacement

ment, and bracing each stack a distance from the bottom against substantial lateral displacement.

2. The method of loading a car which consists in providing a stack of trays having 35 engaging end members, arranging the stacks longitudinally in spaced rows in the car, bracing the rows against longitudinal displacement, and bracing each stack a distance from the bottom against substantial lateral 40 displacement.

3. The method of loading a car which consists in arranging a stack of trays supported against longitudinal movement with relation to each other, arranging the stacks longitudinally in spaced rows in the car, bracing the rows against longitudinal displacement and securing cleats to the ends of the uppermost trays transversely thereof and substantially engaging the sides of the car. 45

4. The method of loading a car which consists in arranging a stack of trays supported against longitudinal movement with relation to each other, arranging the stacks longitudinally in spaced rows in the car, bracing the 50 rows against longitudinal displacement, and bracing the rows against lateral displacement.

ORRIN O. EATON.
